INFUSION PACKAGE AND THE MANUFACTURE THEREOF

Louis Barnett, Brooklyn, N. Y., assignor to Millie Patent Holding Co., Inc., a corporation of New York

Application February 7, 1942, Serial No. 429,894

7 Claims. (Cl. 99—77.1)

This invention relates to the manufacture of filled containers or bags and more particularly is directed to the manufacture of infusion packages, such as tea-balls and the like.

Among the objects of the invention is to generally improve the construction of filled containers or bags in the form of infusion packages as inexpensive articles of manufacture, which shall comprise few and simple parts requiring a minimum of material, which shall be easy and cheap to manufacture in quantity production on automatic high-speed packaging machines, which shall provide an improved form of integral handle, and which article and manufacture thereof shall be practical and efficient to a high degree in use.

This application is a continuation in part of my application, Serial No. 380,628, filed February 26, 1941.

Other objects of this invention will in part be obvious and in part hereinafter pointed out. The invention accordingly consists of features of construction and method, combinations of elements, arrangements of parts and steps in the process of manufacture which will be exemplified in the construction and method hereinafter described and of which the scope of the application will be indicated in the following claims.

In the accompanying drawings in which are shown various possible illustrative embodiments of this invention.

Figs. 1 and 2 are front and side elevational views respectively, showing a manufacture of infusion package embodying the invention;

Figs. 3, 4, and 5 are cross-sectional views taken on lines 3—3, 4—4, and 5—5 respectfully, showing seam joint sealing, seam joint folding and segment-handle slitting operations, respectively;

Figs. 6 and 7 are front and side elevational views respectively, of an infusion package constructed to embody the invention;

Fig. 8 is a cross-sectional view taken on line 8—8 in Fig. 6.

Fig. 9 is a front elevational view similar to Fig. 6 showing the segment-handle extended for suspending the infusion package in brewing;

Fig. 10 is a fragmentary view similar to Fig. 1 showing the manufacture of a modified form of an infusion package with an integral tag terminating the handle embodying the invention;

Fig. 11 is a cross-sectional view taken on lines 11—11 in Fig. 10;

Fig. 12 is an enlarged fragmentary cross-sectional view showing the partial severance of portion of the infusion package for disconnecting the tag end of the handle from the package bag;

Figs. 13 and 14 are views showing infusion packages with integrally formed handles terminated by tags embodying the invention manufactured as shown in Figs. 10 to 12 inclusive, in Fig. 14 the infusion package being shown with the bag thereof in a suspended position; and Fig. 15 is a fragmentary view of a portion of an improved infusion package with a handle terminated by an integrally formed diamond-shaped tag.

Referring in detail to the drawings 20 denotes an infusion package shown in Figs. 6 to 8 inclusive, manufactured to embody the invention.

In practicing the invention for making an infusion package such as a tea-ball 20 on high-speed automatic machines in quantity production, suitable sheet material 21 may be used for making the tea-ball bag which may be supplied from a suitable source such as roll in the form 20 of a web of the required width in the well understood manner, a sufficient length of said web 21 being formed, heat-sealed and cut to form a tea-ball in the manner hereinafter described. Or, pre-cut strips of sheet material 21 of proper 25 shape and length may be provided from a suitable supply source if desired. Sheet material 21 is of foraminous construction, as for example, filter paper, perforated parchment paper or Cellophane, cotton gauze and the like. That used 30 in practice of the invention here described and shown in the drawings may comprise a filter paper base layer 21a coated on one side with a thermosetting "partially fused" plastic lamina 21b of the character described in my said application 35 Serial No. 380,628 or of any other suitable filter sheet base layer having a thermosetting plastic means for forming a heat-sealed "lapped angle" joint seam 24, and bottom and top closure joint 40 seams 25 and 26 all in the manner hereinafter more fully described.

A suitable filter paper sheet for forming base layer 21a may be made of a vegetable fibrous pulp stock, said layer 21a with thermosetting coat or lamina 21b being such that when made 45 into the tea-ball bag has sufficient wet strength to withstand immersion in boiling water without damage or disintegration and without undue loss of tensil strength. The filtering sheet material 21 comprising the layer 21a and coating 50 21b when forming the tea-ball bag must be such as to permit ready infusion, that is, ready passage therethrough of the water of immersion for brewing and straining the filling or tea contents T, said layer 21a, coating 21b, joint seam 24, and closure seams 25 and 26 being of such 55

composition that it is non-toxic, insoluble in hot boiling water, and impart no odor or taste even to the slightest degree to the brew.

It has been found in practice that a 6½ pound fibrous pulp stock sheet of approximately .001 of an inch thick of high wet tensil strength forms a practical filter paper layer 21a for the purposes described herein. On such layer 21a a finely powdered copolymer of vinyl chloride and vinyl acetate may be uniformly sprinkled or sprayed, "partially fused" by heat to 60° C., an pressure rolled thereon for providing a previous, dry and extremely thin coating or lamina 21b which does not materially affect the filtering capacity of the layer 24a. Approximately three ounces of such vinyl powder for each pound of said layer 21a will form coating or lamina 21b of normally less than .0005 of an inch thick.

Sheet material 21 when taken from a roller or precut to the required size has the coating 21b of the folded sheet material 21 positioned to form the interior surfaces of the tea-ball bags so that the "lapped angle" joint seam 24, and closure seams 25 and 26 are sealed on placing said coating 21b thereof in face to face relation and applying pressure and heat to a fusion temperature by suitable clamping or pressure means. With the coating or lamina 21b formed of the "partially fused" vinyl powder permanent sealing fusion will take place when pressure and heat of approximately 130° C. is applied.

In the manufacturing of infusion packages 20 as tea-balls and the like, it has heretofore been found desirable to include as part of the package some form of handle to manipulate the tea-balls during the brewing operation, particularly when carried out in a cup, and also to provide a tag which bears a legend such as the name or trade-mark of the manufacturer, grade of tea, etc. Such handles are most frequently provided by a string or stitched thread attached to the tea-ball bag, the free end of the string handle being terminated by an attached tag. The provision of such string handles and tags in the construction of the conventional tea-balls not only increases the cost of manufacturing by emulsing various additional materials, but also requires in the production process intricate additional steps and when made on high speed automatic machines necessitates the use of complicated expensive apparatus operating at a relatively slower production speed.

In carrying out the improved method for manufacturing infusion packages 20, a pre-shaped strip or the leading end of a web of sheet material 21 may be applied to or wrapped around a former, such as a hollow mandrel or flattened pipe F and joined by abutting aligned edge portions that extend lengthwise centrally along one of the flattened sides of said former F to provide a tubular structure 23, as shown in Figs. 1 to 3 inclusive. Said abutting edge joint portions are permanently secured together by a single "angle" joint seam, or as for example, by forming flange 24a using a suitable pressure thermosetting heat-sealed means P.

The heat sealing pressure means P may be constructed and arranged as shown in Figs. 1, 2, and 3, and is seen to comprise a pair of coating rollers R and R' which form tubular structure 23 about former F with the flange 24a as an upstanding "angle" joint seam. Said rollers R and R' may be undercut as at U and U' respectively, so as to leave only pressure surfaces S and S', respectively, effective for pressure heat

sealing flanges 24a. The heating of said rollers R and R' may be provided in any suitable manner as by electric heater H incorporated in roller R and connected to a power circuit in any well understood manner through conductor wires W.

The web 21 after passing through rollers R and R' to form tubular structure 23 with flange 24a passes under a roller R2 which folds down the flange 24a as at 24b shown in Figs. 1, 2, and 4. The tubular structure 23 thus formed may next pass to a mechanism M which cross folds the flange 24a at 24c (see Fig. 8) and simultaneously through-slits the same at 24d along spaced intervals. For this purpose mechanism M has a grooved fold wheel N cooperating with a circular cutter C, as shown in Figs. 1, 2, and 5. The cutter C is made to terminate in ends C1 so as to leave uncut flange portions 24e between the spaced through-slits 24d. Said mechanism M thus forms a "lapped angle" seam 24 from the "angle" joint seam or flanges 24a, the point along the through-cuts 24d extending along the flat side of the tubular structure 23 being left intact.

As the tubular structure 23 with said through-split seam joint described above continues in its travel it passes between a second set of co-acting rollers D and D' spaced from mechanism M which permanently heat seals the top joint seam closure 26 of a leading finished infusion package 20 and the bottom joint seam closure of an other infusion package in the making, as is clearly shown in Figs. 1 and 2. Said rollers D and D' have raised complementary corrugated pressure surfaced portions S2 and S3, respectively for forming said seam joint top and bottom closures 25 and 26. The roller D may carry a straight blade or knife K mounted to extend across the pressure surface portions S2 and S3 to cut through and separate the sealed top closure 25 of the leading package 20 from the bottom closure of the next succeeding package. Suitable heating means such as electric heater H' provided with conductor wires W' may be incorporated in roller D as shown in Figs. 1 and 2 for heating the pressure surface portions S2 and S3.

Between the mechanism M and the set of rollers D and D', above the latter as seen from Fig. 1, the flattened pipe F terminates in a tapered spout E through which measured quantities of essence containing products, such as tea T, is delivered from suitable apparatus of any conventional construction (not shown), in the well understood manner. Each bag of the infusion package being manufactured by means of said spout E is charged with tea T, preferably by only partially filling the bag after permanently sealing the joint seam closures 25 and 26 of leading infusion package 20. Each bag of the infusion package being manufactured by means of said spout E is charged with tea T, preferably by only partially filling the bag after permanently sealing the joint seam closures 25 and 26 of leading infusion package 20, and then said bag passes through rollers D and D'.

The through-slit 24d has one end terminating at uncut portion 24c short of the edge of the top closure 25 of each package 20 so as to leave a segment-handle 24f integrally connected with the flange 24, while the other end of said through-slit 24d extends to the marginal edge of the bottom closure 26 thus permitting the handle 24f to be moved to the position as shown in Fig. 9 when suspending the package 20 for brewing.

See also the full line and dotted line positions in Fig. 7.

In the manufacture of infusion packages 20, indicia 29 may be provided, as for example imprinted on the top closure seam joint 25. It may also be desirable to provide an integral tag terminating the segment-handle for such indicia 29. To this end a modified manufacture embodying the invention can be utilized in producing infusion packages 120. Said infusion package 120 has a top joint seam closure 125, a bottom joint seam closure 126, and a segment handle 124f terminated by a tag portion 124g as shown in Figs. 10 to 14 inclusive.

In this modification, the tubular structure 23 is formed on flattened pipe F using a heat sealing pressure means, a fold roller, like P and R2, respectively, as described above for manufacturing infusion package 20 shown in Figs. 1 and 2, and mechanism similar to mechanism M except the end C2 on the circular cutter C are spaced apart a greater distance than in cutter ends C1.

To form the top and bottom heat sealed joint closures 125 and 126 respectively, rollers D2 and D3 may be substituted for rollers D and D1 respectively, these rollers D2 and D3 have two spaced blades or knives K2 and K3 mounted on roller D2 instead of a knife K as provided on roller D. These knives K2 and K3 extend across the pressure surface portions S4 and S5, of rollers D2 and D3, respectively, the distance between the blades being made the width of the tag portion 124g. Knife K1 serves the same function as knife K described above, that is for completely cutting off the finished leading infusion package 120. While knife K2 only partially cross cuts through the material at 124h as shown in Figs. 11 and 12 to intersect with the upper end of the longitudinal through-slit 124d, the other end of the latter terminating short of the edge of top closure 125 at the attachment 124e. Thus there is provided a construction of infusion package 120 which permits swinging the handle 124f terminated by integral tag portion 124g with relation to the package bag for suspending the package in brewing as shown in Figs. 13 and 14.

In Fig. 15 a fragmentary portion of an infusion package 220 is shown in which the integral tag portion 224g is shaped, that is, made in a desired configuration, as for example diamond-shaped cut by using two or more knives in place of knives K2 and K3 conforming with such desired shapes for cutting away portions as indicated by dot and dash lines in Fig. 15.

Tea-balls 20, 120, and 220 are each manufactured as described above in the embodiments of the invention whether or not made with a tag integrally terminating the segment-handle as cut from the heat sealed joint seams forming the tubular structures of the package bags yet leaving the closures of such cut joint seams intact.

It is therefore seen that there is provided an improved method and article of manufacture in which the several objects of the invention are achieved and which are well adapted to meet the conditions of practical use.

As various other possible embodiments of the invention may be made in the above invention and as various changes may be made in the embodiments and method above set forth it is to be understood that all matters herein set forth and shown in the accompanying drawings are to be interpreted as illustrative and not in a limited sense.

Having thus described my invention I claim as new and desire to secure by Letters Patent:

1. A method of manufacturing infusion packages of the character described consisting of aligning, abutting and securing opposite free edges of a filter sheet material to form a single "angle" joint seam of a tubular structure with said joint seam extending the length thereof, sealing one end of said structure to provide a bag with a tight bottom closure and an open end, filling said bag through the said open end with an essence containing a product, through-slitting the "angle" joint seam along a mid-portion the length thereof short of complete severance at said open end to provide an integral segment-handle while retaining the bottom closure and "angle" joint seam intact, and sealing said open end to form a tight top closure.
2. The method defined in claim 1, including the step of folding the "angle" joint seam against the tubular structure of the bag to form a "lapped angle" joint seam thereat leaving the cut portions of said joint seam forming the segment-handle positioned for movement toward and away from said structure.
3. An article of the character described comprising an infusion package having a flattened tubular bag structure formed of a strip of filtering sheet material with a single "lapped angle" joint seam extending centrally along the length of a flat side thereof and top and bottom closures, a dissolvable product enclosed in said bag structure, said seam joint having a through-slit extending along a mid-portion thereof from the bottom closure short of complete severance at the top closure to provide an integral handle while retaining said top, bottom and seam joint closures intact.
4. An infusion package of the character described comprising a flattened tubular bag structure of filtering sheet material formed with a seam joint extending the length thereof and intersecting top and bottom closures, as essence containing product partially filling said bag, said seam joint having a through-split in a mid-portion thereof extending up from the bottom closure to terminate short of complete severance at the top closure thereby providing an integral segment-handle for suspending the package in brewing manipulations.
5. An infusion package as defined in claim 4 in which said through-split is extended laterally to sever a portion of the material forming said bag bottom closure for providing an integral tag terminating said segment-handle while retaining the bottom closure intact.
6. An infusion package of the character described comprising a flattened tubular bag formed of filtering sheet material having top and bottom sealed closures and an "angle" joint seam extending lengthwise of the flat side of the bag, an essence containing product enclosed in said bag, and an integrally formed segment-handle split from a portion of said "angle" joint seam connecting with said top closure positioned for movement toward and away from said bag side while retaining said closures and joint seam intact.
7. An infusion package as defined in claim 6 which includes a tag formed from a severed portion of the bottom sealed closure to terminate the segment-handle as an integral part thereof.

LOUIS BARNETT.
